UNITED STATES PATENT OFFICE.

ROBERT ROWE, OF BRENTWOOD, NEW HAMPSHIRE.

DESIGN FOR VEHICLE HUB-BAND.

Specification forming part of Design No. 7,392, dated April 21, 1874; application filed January 6, 1874.

[Term of Patent 7 years.]

To all whom it may concern:

Be it known that I, ROBERT ROWE, of Brentwood, in the county of Rockingham, State of New Hampshire, have invented a Design for Carriage-Wheel Hubs, of which the following is a specification:

The nature of my design is fully represented in the accompanying illustration, to which reference is made.

In said illustration, A is the wooden hub of the wheel, provided with the cast-iron spoke-holder or band B, in the usual manner. The flange of the band is provided with a series of

imitation screw-heads, a a, arranged around the hub, and also with a series of radial points, c c, each point having two of the imitation screw-heads, or one upon either side, as shown.

What I claim as my invention is—

The design for a carriage-wheel hub-band or spoke-holder, ornamented with imitation screw heads and points, substantially as set forth and specified.

ROBERT ROWE.
